THOMAS EDMUND HOLMES, OF GLASGOW, SCOTLAND

INSTALLATION FOR FORCING VISCOUS FLUID INTO CONTAINERS

Application filed February 26, 1930, Serial No. 431,554, and in Great Britain March 1, 1929.

The subject of this invention is an installation for forcing a thick viscous fluid into a receiver at a high pressure such that the viscous fluid cannot be pumped by an ordinary pump.

The invention consists in an installation for this purpose comprising one or more hydraulic forcing rams having a hydraulic cylinder or cylinders and, opposed thereto, 10 a cylinder or cylinders for viscous fluid, power operated inlet and delivery valves for the viscous fluid cylinder or for each viscous fluid cylinder, and means associated with the hydraulic cylinder or cylinders for controlling said valves.

It is understood that when a plurality of forcing rams is provided these rams are arranged to operate out of phase.

In effect the hydraulic forcing ram or each 20 such ram constitutes an intensifier, the fluid at the high pressure end of which is the viscous fluid in question.

The viscous fluid is delivered from a tank or other source of supply to the forcing ram cylinder or cylinders during the return stroke of the forcing ram or rams effected by the power of drawback rams; such delivery being effected, for example, by gravity or by a 25 pump.

30 The return stroke of the forcing ram or of each ram is timed to commence by continuously rotating timing means operatively connected to trip gear associated with mechanically operated pressure and exhaust valves 35 for the low pressure cylinder of the forcing ram. Thus, as the forcing ram attains the end of its forward stroke, the trip gear is operated by the timing means whereby the valves are operated so that the hydraulic cylinder, i. e., the low pressure cylinder, of the 40 forcing ram is closed to pressure and open to exhaust; concomitantly therewith the power operated inlet and delivery valves interposed in the connection for viscous fluid

45 are automatically opened and closed, respectively. At the moment the return stroke is completed, the forcing ram cylinder being now full of viscous fluid supplied during the return stroke of the ram, the trip gear is engaged by a tappet on the ram whereby a

55 weightd lever is released to effect reversal of the positions of the pressure and exhaust valves. Pressure water is now re-admitted to the hydraulic cylinder of the forcing ram and the positions of the inlet and delivery valves are reversed so that the forcing ram again commences to deliver viscous fluid into the receiver.

In the accompanying drawings Figs. 1 and 1a show, more or less diagrammatically, part 60 of an installation constructed in accordance with the invention; Fig. 2 is a fragmentary diagrammatic view; and Fig. 3 is an axial section through a working valve chest.

The installation includes three hydraulic 65 forcing rams of which one only is indicated generally at A (Fig. 1). Each forcing ram comprises a differential ram proper presenting a high pressure end 1 operating on the viscous fluid and working in a cylinder 2, 70 and a low pressure end 3 working in a cylinder 4. Associated with the cylinder 4 are two continuously loaded drawback rams 5 working in cylinders 6 and unitary with rods 7 attached to a crosshead 8 carried by the 75 ram 1, 3.

Attached to the cylinder 2 is a valve chest 9 accommodating a non-return valve 10 adapted to control the inlet of viscous fluid to the cylinder 2 and a non-return delivery 80 valve 11. The valve rod 12 of the inlet valve 10 is aligned with and connected to a piston rod 13 presenting a piston 13' operating in a cylinder 14 to the opposite ends of which are connected conduits 15, 16. The valve 85 rod 17 of the delivery valve 11 is aligned with and connected to a piston rod 18 presenting a piston 18' operating in a cylinder 19 to the opposite ends of which are connected conduits 20, 21.

90 The conduit 16 is connected to the conduit 20. Common to said conduits 16, 20 is a spring-urged relief valve 22. The conduits 15, 21 are connected to a common conduit 23. 24 denotes a valved connection between 95 the conduit 20 and a conduit 25 led to a source of water supply at a pressure of say 800 lbs. per square inch. It will be seen that pressure water entering the cylinder 14 by way of the conduit 15 acts on the full area presented by 100

the piston 13' to close the valve 10, and that pressure water entering the cylinder 14 by way of the conduit 16 acts on the difference in areas of the piston and piston rod 13', 13, respectively, to open the valve 10. Pressure water entering the cylinder 19 by way of the conduit 21 acts on the full area presented by the piston 18' to open the valve 11. Pressure water entering the cylinder 19 by way 10 of the conduit 20 acts on the difference in areas of the piston and piston rod 18', 18, respectively, to close the valve 11.

To ensure fluid tightness, the pistons 13', 18' are provided with packing 28.

29 denotes a valve chest in which are operable a pressure valve 30, an exhaust valve 31, a non-return valve 32, and a spring-loaded valve 33 (Fig. 3). An inlet branch 34 of the valve chest 29 is connected by way of a 20 conduit 35 to the discharge of hydraulic pumps indicated generally at B (Fig. 2) and having a working pressure of say 1500 lbs. per square inch. Interposed at spaced 25 points in the conduit 35 are two valves indicated at 36. A chamber 37 of the valve chest 29 is connected by way of a conduit 38 to the hydraulic cylinder 4, said conduit 38 being provided with a drain valve 39. A chamber 40 of the valve chest 29 is connected 30 to the end of the conduit 23 remote from the cylinders 14, 19. A chamber 41 of the chest 29 is connected to an exhaust conduit 41' branching into a conduit 42 leading from a water storage tank 43. The hydraulic 35 pumps B draw from the conduit 42 by way of a conduit 44 fitted with a valve 45. 46 denotes a valve interposed in the conduit 41'. 47 denotes a by-pass valve interposed in a conduit 48 interconnecting the conduits 35, 40 44. 48' denotes a conduit extending between the conduit 35 and a by-pass valve chest 49 and controlled by a needle valve 50. Accommodated in the valve chest 49 is a by-pass valve 51 adapted to control passage of water 45 from the conduit 48' to the conduit 42 by way of a conduit 52 connecting said conduit 42 to the valve chest 49. Integral with the valve 51 is a plunger 53 working in a chamber 54 connected by way of a conduit 55 and a 50 branch conduit 55' to the chamber 40 of the valve chest 29, there being interposed in the branch conduit 55' a valve 56. 57 denotes a pressure water supply conduit leading from the conduit 35 to the valve chests 55 29 of the hydraulic forcing rams A. Branching from the conduit 25 is a conduit 58 connected to the cylinders 6 by way of conduits 59, 60 with which is associated a spring-urged relief valve 61. 62 denotes a valve interposed between the conduits 58 and 59. 63 denotes a drain valve fitted to the conduit 59.

The valves 30-33 are urged towards their seats by helical compression springs 64-67, respectively. The lower ends of the stems 65 30', 31', respectively, of the valves 30, 31

present abutment faces 68, 69, respectively, engageable by set screws 70, 71 adjustably mounted in a three-armed lever 72, 73, 74 fulcrumed at 75 beneath the valve chest 29. The arm 73 of said lever is operatively connected by means of a link 76 to the upper end of a lever 77 pivoted between its ends at 78 in a bracket 79. Mounted on the lower end of the lever 77 is a follower 80 cooperating with a continuously rotating cam 81 secured to a shaft 82 journalled for rotation in the bracket 79 and carrying a worm wheel 83 meshing with a worm 84 on a shaft 85 driven by an electric motor 86 through the intermediary of gears 87, 88. The arm 74 70 of the lever 72, 73, 74 carries an adjustable counterweight 89. The lower end of the lever arm 72 presents a toe 90 engaging a slot 91 in a shaft 92 slidable horizontally in brackets 93, 94 and connected to the piston 95 of a dashpot cylinder 96. 97 denotes a spring-urged vertically movable detent mounted in the bracket 94 and cooperating with a notch and groove in the shaft 92. The detent 97 is engaged by the arm 98 of a bell-crank 90 lever 98, 99, pivoted at 100 in the bracket 94. The lever arm 99 is operatively connected by means of a link 101 to one end of a lever 102 pivoted between its ends at 103 and operatively connected at its other end to a horizontally slidable tappet rod 104 engageable by a tappet 105 carried by the crosshead 8.

In operation, the return stroke of the ram 1, 3, i. e., the stroke in the direction indicated by the arrow a, (Fig. 1) is effected by the continuously loaded drawback rams 5 which are exposed to the pressure of 800 lbs. per square inch. The position of the trip gear 92-104 is such that the set screw 71 is in engagement with the lower end 69 of the exhaust valve 31 whereby to maintain said valve in open position in opposition to the action of the spring 65; the set screw 70 being clear of the lower end 68 of the valve stem 30'. Exhaust from the cylinder 4 passes 100 by way of the conduit 38 into the chamber 37, whence it flows by way of the non-return valve 32, chamber 40, exhaust valve 31, chamber 41 and the conduits 41', 42 to the storage tank 43.

110 During the return stroke of the ram 1, 3 viscous fluid is allowed to flow under gravity into or is pumped by means of a pump associated with a weighted storage vessel into the cylinder 2 by way of the inlet valve 10 120 which is maintained in open position by pressure from the conduit 16 acting on the difference in areas of the piston and piston rod 13', 13, respectively, the delivery valve 11 being maintained in closed position.

125 Towards the end of the return stroke, the tappet 105 on the crosshead 8 engages the tappet rod 104 and rocks the bell-crank lever 98, 99 on its pivot 100 whereby to retract the spring-urged detent 97 from locking engage- 130

ment with the shaft 92, whereupon said shaft is displaced endwise and the lever 72, 73, 74 is rocked on its pivot 75 under the action of the counterweight 89. The set screw 71 is disengaged from the end 69 of the valve stem 31' whereby the valve 31 is closed under the action of the spring 65. The set screw 70 engages the end 68 of the valve stem 30' and opens the valve 30 in opposition to the action of the spring 64. Pressure water from the pumps B passes by way of the conduit 35, the branch 34 and the valve 30, to the chamber 40 of the valve chest 29 whence it flows by way of the conduits 55', 55 to the chamber 54 of the by-pass valve piston 53, and, acting on said piston, closes the by-pass valve 51 to prevent leakage of pressure water from the conduit 35 to the storage tank 43 by way of the conduit 48, needle valve 50, by-pass valve 51 and conduit 52.

Pressure water also flows from the chamber 40, by way of the conduit 23, to the cylinders 14, 19, and acts on the full areas presented by the pistons 13', 18'.

When the water pressure in the chamber 40 attains a predetermined intensity, sufficient to close the inlet valve 10 but not to open the delivery valve 11, the valve 33 opens in opposition to the action of the spring 67 under the action of the pressure on a shoulder 106 presented by said valve 33. Pressure water is now admitted to the cylinder 4 by way of the valve 33, chamber 37 and conduit 38. When the total resistance offered to the opening of the delivery valve 11 is overcome said valve opens.

In the forward stroke of the ram 1, 3, the viscous fluid is ejected from the cylinder 2 to the receiver by way of the delivery valve 11.

The next return stroke of the ram 1, 3 is timed to commence by the continuously rotating cam 81 which functions to effect closure of the valve 30 and opening of the valve 31 by restoring the trip gear to position ready to be re-tripped by the tappet 105 towards the end of said next return stroke.

It will be understood that, on release of the trip gear by the detent 97, the dashpot piston 95 cushions the movements of the lever 72, 73, 74 under the influence of the weight 89.

What I claim is:

1. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, and fluid pressure means for operating said inlet and delivery valves.

2. An installation for forcing viscous liquid into a receiver, comprising a hydraulic cylinder, a cylinder for viscous liquid adjoined

with said hydraulic cylinder, a forcing ram presenting a high pressure end working in said cylinder for viscous liquid and a low pressure end working in said hydraulic cylinder, inlet and delivery valves for said cylinder for viscous liquid, hydraulic valves controlling the passage of fluid to and from said hydraulic cylinder, and means including pressure fluid connections between said hydraulic valves and said inlet and delivery valves for operating said inlet and delivery valves.

3. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, hydraulic valves controlling the passage of fluid to and from said hydraulic cylinder, means associated with said ram for actuating said hydraulic valves, means including pressure fluid connections between said hydraulic valves and said inlet and delivery valves for operating said inlet and delivery valves, a drawback ram for effecting the return stroke of said forcing ram, and a cylinder in which said drawback ram operates.

4. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, a pressure valve and an exhaust valve controlling the passage of fluid to and from said hydraulic cylinder, means adapted to be tripped in the return stroke of said forcing ram for operating said pressure valve and exhaust valve, and means including pressure fluid connections between said last mentioned valves and said inlet and delivery valves for operating said inlet and delivery valves.

5. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, a pressure valve and an exhaust valve controlling passage of fluid to and from said hydraulic cylinder, a spring-loaded valve between said pressure valve and said hydraulic cylinder, mechanically actuated means for operating said pressure valve and exhaust valve, and means including pressure fluid connections between

said pressure and exhaust valves and said inlet and delivery valves for operating said inlet and delivery valves.

6. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, a pressure valve and exhaust valve controlling the passage of fluid to and from said hydraulic cylinder, an automatic non-return exhaust valve between said pressure valve and said hydraulic cylinder, mechanically actuated means for operating said pressure valve and said first mentioned exhaust valve, and means including pressure fluid connections between said pressure valve and said first mentioned exhaust valve and said inlet and delivery valves for operating said inlet and delivery valves.

7. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, means including pressure fluid connections to said valves for operating said valves, valves controlling admission of pressure fluid to said hydraulic cylinder and to pressure fluid connections, and trip mechanism released by said ram controlling said last mentioned valves.

8. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, mechanically operated pressure and exhaust valves controlling the passage of fluid to and from said hydraulic cylinder, means including pressure fluid connections between said last mentioned valves and said inlet and delivery valves for operating said inlet and delivery valves, a draw-back ram for effecting the return stroke of said forming ram, and a cylinder in which said drawback ram operates.

9. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, hydraulic valves

controlling the passage of fluid to and from said hydraulic cylinder, means including pressure fluid connections between said hydraulic valves and said inlet and delivery valves for operating said inlet and delivery valves, means including trip mechanism released by said ram for controlling said hydraulic valves, and cam means for restoring said trip mechanism to initial position after release by said ram.

10. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, hydraulic valves controlling the passage of fluid to and from said hydraulic cylinder, means including pressure fluid connections between said hydraulic valves and said inlet and delivery valves for operating said inlet and delivery valves, trip mechanism released by said ram for effecting one-way movement of said hydraulic valves, and power means for effecting reverse movement of said hydraulic valves.

11. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, hydraulic valves controlling the passage of fluid to and from said hydraulic cylinder, means including pressure fluid connections between said hydraulic valves and said inlet and delivery valves for operating said inlet and delivery valves, mechanism released by said ram for effecting one-way movement of said hydraulic valves, and power means for effecting reverse movement of said hydraulic valves and for restoring said trip mechanism to initial position after release by said ram.

12. An installation for forcing viscous liquid into a receiver, comprising a hydraulic cylinder, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, a piston connected to said inlet valve, a piston connected to said delivery valve, two operating cylinders each receiving one of said pistons, hydraulic valves controlling the passage of fluid to and from said hydraulic cylinder, connections between said hydraulic valves and one end of each of said operating cylinders, connections for

fluid under pressure taken to the opposite ends of said operating cylinders, means including trip mechanism released by said ram for actuating said hydraulic valves, and cam means for resetting said trip mechanism to initial position after release by said ram.

13. An installation for forcing viscous liquid into a receiver, comprising a hydraulic cylinder, a pump, pipe connections between said pump and said hydraulic cylinder, a by-pass valve included in said connections, a cylinder for viscous liquid adjoined with said hydraulic cylinder, a forcing ram presenting a high pressure end working in said cylinder for viscous liquid and a low pressure end working in said hydraulic cylinder, inlet and delivery valves for said cylinder for viscous liquid, and fluid pressure means for operating said inlet and delivery valves.

20. In testimony whereof I have signed my name to this specification.
